Primary Examiner — Cynthia R Underwood*(74) Attorney, Agent, or Firm* — Lerner, David, Littenberg, Krumholz & Mentlik, LLP**CLAIM**

The ornamental design for a pigtail strain relief device, as shown and described.

DESCRIPTION

FIG. 1 is a perspective view of a pigtail strain relief device according to a first embodiment of my design;

FIG. 2 is a front view of the first embodiment;

FIG. 3 is a rear view of the first embodiment;

FIG. 4 is a left side view of the first embodiment;

FIG. 5 is a right side view of the first embodiment;

FIG. 6 is a top view of the first embodiment;

FIG. 7 is a bottom view of the first embodiment;

FIG. 8 is a perspective view of a pigtail strain relief device according to a second embodiment of my design;

FIG. 9 is a front view of the second embodiment;

FIG. 10 is a rear view of the second embodiment;

FIG. 11 is a left side view of the second embodiment;

FIG. 12 is a right side view of the second embodiment;

FIG. 13 is a top view of the second embodiment; and,

FIG. 14 is a bottom view of the second embodiment.

Broken lines are environmental only and form no part of the claimed design.
